Dec. 1st

John F. Rathbone, Albany, New York,
Inventor of the Patent Stone, doth hereby state,

The subscriber invented the above Patent Stone, a very part of the same.

That when it may please the Honorable John F. Rathbone of Albany in the County of Albany and State of New York, have invented a new and useful design for a writing Stone and I do hereby declare that the accompanying drawings are full and accurate representations of a stone after my said design, Fig. 1, being a front and Fig. 2, a side view of the same, & is a section of the writing upon the even and flat door. Both sides are alike and the back entirely plain.

What I claim as my invention and distinct from by other Patent is, the configuration of parts and arrangement of ornamental form represented in the accompanying drawings forming a design for a writing Stone.
